(57) CLAIM

The ornamental design for a floor lamp as shown and described.

DESCRIPTION

1. Floor lamp

1.1: Perspective

1.2: Left

1.3: Right

1.4: Front

1.5: Rear

1.6: Top

1.7: Bottom

1.8: Enlarged view of the portion of FIG. 1.7 within dot-dash broken lines

The dashed broken lines in the figures show portions of the floor lamp that form no part of the claimed design.

The dot-dash broken lines in the figures show the boundaries of the enlarged view and form no part of the claimed design.

1 Claim, 5 Drawing Sheets
